UNITED STATES PATENT OFFICE.

GEORGE A. MEAD, OF MANSFIELD, OHIO, ASSIGNOR TO THE OHIO BRASS COMPANY, OF MANSFIELD, OHIO, A CORPORATION OF NEW JERSEY.

ELECTRICALLY-OPERATED TRACK SWITCH.

Application filed December 7, 1923. Serial No. 679,099.

To all whom it may concern:

Be it known that I, GEORGE A. MEAD, a citizen of the United States of America, residing at Mansfield, in the county of Rich-
5 land and State of Ohio, have invented cer-
tain new and useful Improvements in an
Electrically-Operated Track Switch, of
which the following is a specification.

My invention relates to an electrical sys-
10 tem for operating switches and is particu-
larly adapted to the operation of track
switches by the operator upon a car.

One of the objects of my invention is to
15 provide means for automatically operating
the track switch from the car through the
medium of the motor controller when
thrown to either "power on" or "power off"
the motors.

Another object of my invention is to sup-
20 ply current to the system for a predeter-
mined period of time and regardless of the
position of the car after having once set the
system in operation.

Another object of my invention is to pre-
25 vent the track switch being thrown to the
wrong position after being initially set to
the correct position.

A still further object of my invention is
30 to prevent the burning out of the track
switch operating mechanism.

A still further object is to prevent the
breaking of destructive arcs by the current
collector or trolley wheel.

Other objects will disclose themselves as
35 further disclosure of my invention is made
herein.

My invention resides in the new and novel
construction, combination and relation of
various parts and circuits herein described
40 and shown in the drawings.

In the drawings accompanying this speci-
fication:

Fig. 1 shows a diagrammatic scheme of
the circuits employed in a car and which
45 are taken into account in the operation of
my invention as more fully described here-
inafter.

Fig. 2 is a schematic drawing of my in-
vention showing the relation of the various
50 parts and circuits when the system is in
normal condition, that is, before and after
its operation for positioning the track

switch. The switch tongue, however, may
be in any of its positions.

Fig. 3 is a schematic drawing of my in-
vention showing the arrangement of the
parts and circuits immediately after it has
been set in operation by the car operator
turning his controller to "power off".

Fig. 4 is a schematic drawing of my in-
vention showing the arrangement of the vari-
ous parts and circuits after a predeter-
mined time after the system has been set in
operation by the car operator setting his
controller to "power off" position.

Fig. 5 is a schematic drawing showing the
arrangement of parts and circuits when the
system has been set in operation by the oper-
ator setting his controller to the "power on"
position.

Referring to Fig. 1, it is the object of
my invention to provide a system by means
of which the track switch is automatically
and electrically operated to its "straight
70 ahead" or "curve" position as may be de-
sired by the car operator merely applying
"power on" or "power off" to his motors by
means of his regular motor controller. The
system utilizes the principle that when the
75 controller is set to "power off" no current
is flowing through the motors and when the
controller is set to "power on" heavy cur-
rent will flow through the motors. The flow
and non-flow of current is made use of in
the operation of the system for setting in
80 operation and properly positioning the
switch tongue. There are other currents
flowing through the car motor which must
be taken into account in the designing of
the system and which are not under the con-
85 trol of the car operator, or rather are not
controlled by the car controller. These are
what are known as the heat, light, air com-
pressor circuit, etc., and which I shall re-
fer to as the auxiliary car circuits.

In Fig. 1 W represents the trolley wheel
or current collector and T represents the
trolley pole by means of which the cur-
rent collector is mounted upon the car. H
indicates the heaters, L indicates the lights
and F indicates the air compressor circuit
and these circuits when all in operation, to-
gether with possibly others, may carry a
total of a considerable amount of current.

The motors for moving the car are indicated by M and the switch by which the current through the motors is controlled is indicated by C. All of the circuits within the 5 car are connected to the ground.

In the preferred embodiment of my invention, which is shown in normal condition in Fig. 2, P indicates a trolley pan which is positioned in connection with the 10 trolley conductor 1 so that the current collector may pass from the trolley wire on to the pan P and out of engagement with the trolley conductor and pass off of the pan P and back into engagement with the trolley 15 conductor 1. The pan P comprises two laterally spaced parallel contact members 2 and 3 which are normally insulated from each other, but so positioned that the current collector may bridge the two in passing 20 thereover. I employ a track switch S which is provided with a switch tongue 4. The electrical operating mechanism for the tongue 4 comprises two solenoids 5 and 6, one terminal of each solenoid being connected to the ground G through the conductor 7. Reciprocally operating within the 25 solenoid is a plunger 8 which is drawn in when solenoid 5 is energized and drawn out when solenoid 6 is energized and which is 30 connected to the switch tongue and therefore moves the tongue to one or the other of its positions.

I also employ an electrically operated 35 switch A, which I will term a selector switch, as its function is to place one or the other of the solenoids 5 or 6 in circuit when the current collector engages the pan P. The switch A is provided with a coil 9 mounted upon an iron core and having one terminal 40 connected to the trolley wire 1 by the conductor 10, and having its other terminal connected to the contact member 3 by means of the conductors 11 and 12. The coil 9 I prefer to make of a few turns of heavy wire as 45 it must withstand a heavy current flowing therethrough and it must also have its ampere turns so proportioned that it will operate to raise the switch arm 13 when the controller C is turned to the "power on" position with the collector in engagement with the pan P and which will not raise the arm 13 when the controller is turned to the "power off" position. Also the ampere turns 50 must be so adjusted that the current flowing through the auxiliary circuits and which will flow through the coil 9 will not operate to raise the arm 13 when the collector engages the pan P and the controller is set to "power off". It will be seen that the 55 contact member 3 is always in electrical connection with the trolley wire 1 and when the current collector engages the pan P with "power on" current will flow from the trolley wire to the contact member 3 through the 60 current collector W, trolley pole T, controller 65

C, motors M to the ground at the same time the contact member 2 will be electrically connected to the trolley wire 1 through the medium of the current collector. The switch A is also provided with two contacts 14 and 15 and the switch arm 13 is normally in engagement with the contact 15 so that the selector switch is normally set for connecting the system to the solenoid 5 and will so remain set if the collector engages the pan with "power off". It will also be seen that when the switch arm 13 engages the terminal 14 through the application of "power on" when the collector engages the pan P that the solenoid 6 is placed in circuit with the 70 system. I also employ an electrically operated switch B which is provided with a coil 16 mounted upon a magnetic core and has one terminal connected to the contact member 2 by the conductor 17, and the other terminal connected to the ground G by means of the conductor 18. It is not necessary that the conductor 18 shall be connected directly to the ground, but it may be connected to any other point in the system which 75 will give it a ground connection and without interfering with the functioning of the various parts as required. The resistance of the coil 16 may be sufficiently high so that only a small current flows therethrough, 80 therefore, when the collector leaves the pan P only a slight arcing will take place.

It will be evident that when the pan P is engaged by the current collector with either "power on" or "power off" that current will flow through the coil 16 thereby energizing the same and picking up the arm 19, and that the arm 19 will be held in a raised position by the coil 16 as long as the current collector engages the pan P. The switch arm 19 is connected to the trolley conductor 1 by means of the conductors 20 and 21. The conductor 21 can, however, be connected to the conductor 10 or it may be connected to the contactor 3 although I do not prefer this latter connection as then any current flowing through the conductor 21 will flow through the coil 9 and will merely add to the auxiliary car circuit current and, therefore, tend to make it more difficult to 100 properly adjust the winding of the coil 9. When the arm 19 is raised it engages the contacts 22 and 23. The contact 23 is connected by the conductor 24 to one terminal of the coil 25 and the other terminal of the coil 25 is connected to the arm 13 by the conductor 26. It will be seen that whenever the arm 19 engages the contact 23 and current is flowing therethrough that the coil 25 will be energized and as coil 25 is not wound to act differentially with coil 16 it becomes a holding coil and will maintain the arm 19 in engagement with the contact 23 whenever current is flowing therethrough and regardless of whether current 105 110 115 120 125 130

is flowing through the coil 16. The resistance of the coil 25 can be made comparatively low and carry the current necessary for the operation of the solenoids 5 and 6 which may amount to six to ten amperes.

I also employ the switch C provided with a time lag in opening which functions to maintain the branch circuit from the contact 15 to the solenoid 5 normally closed and to open this circuit after a predetermined time after the switch B has closed. The switch C comprises two coils 27 and 28 differentially connected and of comparatively high resistance so as to permit only a small current to pass therethrough as this current flows through the solenoid 5 and must, therefore, not effect the operation of the solenoid. One end of each coil 27 and 28 is connected to the switch arm 29 through the conductor 30, 20 and the switch arm 29 is connected to the remaining terminal of the solenoid 5 by the conductor 31. It will be noted that the conductors 30, 31, solenoid 5 and conductor 7 form a ground connection for the coils 27 and 28. The remaining terminal of coil 28 is connected to the source of power through the conductors 32 and 21 and it will be evident that the coil 28 is normally energized and will therefore, attract and maintain the arm 29 in engagement with the contact 33 under normal conditions. The remaining terminal of the coil 27 is connected to the switch arm 13 through the conductor 34 and it is evident that the coil 27 will have a connection with the source of power whenever the arm 19 is closed through the conductors 34, 26, coil 25, conductor 24, arm 19 and conductors 20 and 21. When, however, the arm 19 is closed and the arm 13 engages the contact 15 the arm 29 will be of substantially the same polarity as the trolley conductor 1 as these two are connected through a low resistance circuit comprising the elements 21, 20, 19, 24, 25, 26, 13, 15, 35 and 33. It will be evident from this that the conductors 30 and 32 will be connected to points of electrically equal polarity, therefore, the current which has been flowing through the coil 28 will cease as there has been substantially a shunt placed across the terminals of this coil and as the same is true of the coil 27 through its connection with the arms 13 and 29 no current will flow through this coil and, therefore, the arm 29 will drop after a predetermined time lag due to the dissipation of residual magnetism in the core or other holding means. As soon, however, as the arm 29 has dropped the difference of potential between the arm 29 and the trolley conductor 1 will be a maximum and also the same is true between the arm 13 and the arm 29, and current will flow through each coil 27 and 28 but in opposite directions, and the arm 29 will be maintained in open position through the differential action of the ener-

gized coils 27 and 28 so long as the arm 19 remains closed.

It will be evident that when the switch B has been closed by a current collector engaging the pan P with "power off" and energizing the coil 16, that the arm 19 will be placed in engagement with the contact 23, and current will then flow through the solenoid 5 and the plunger 8 will be drawn inwardly and the track switch tongue moved to the "straight ahead" position. It will also be evident that as long as the contactor engages the pan with "power off" that the coil 16 will be energized and the arm 19 held in a closed position. As soon as the arm 19 is closed and current is flowing through the coil 25 the coil 25 will function as a stick or holding coil, and it will of itself maintain the arm 19 in a raised position as long as current is flowing through the circuit. The circuit will remain closed as long as the arm 29 is in engagement with the contact 33, but, as already explained, after a predetermined time after the closing of the arm 19 the arm 29 will open thereby opening the circuit through the coil 25 and the solenoid 5, and the arm 29 will drop providing the contactor is in engagement with the pan P. If it is, the arm 29 will be maintained open through the arm 19 being closed, but current will not flow through the coil 5 other than the current in the coils 27 and 28.

The arrangement of the parts immediately after the opening of the switch C, as just described, is shown in Fig. 4. If the contactor should be off the pan before the switch 29 opens the current flowing through the coil 25 will maintain the arm 19 closed and the arm 29 will function to open the circuit through the coils 25 and 5, and as soon as this takes place the coil 25 will become deenergized and the switch arm 19 will drop, but the arm 29 will be immediately raised upon the dropping of the arm 19 as the coil 27 of the switch C will be deprived of its energizing current, but the current will continue to flow through the coil 28 which will pick up the arm 29 and the system will then be returned to its normal condition.

While current is flowing through the system, as just described, with the arm 13 in engagement with the contact 15 current will also flow through the coil 36 as it has its terminals connected to the conductor 35 and the contact 14 through the circuit comprising the conductors 37, resistance 38, conductor 39 and the conductor 40 respectively. As a terminal 14 is connected to the remaining terminal of the solenoid 6 by the conductor 41, this furnishes a ground connection for the coil 36 which receives current from the conductor 35. The coil 36 is so connected that it acts differentially to the coil 9 when it is energized with the arm 13

in engagement with the contact 15. The ampere turns, however, of the coil 36 are so proportioned that the coil 36 will not pick up the arm 13, but will act only as a holding coil for the arm 13. In order to properly adjust the ampere turns in this circuit, which is of comparatively high resistance so as not to affect solenoid 6, I may introduce in the circuit an external resistance 38 by means of 10 which the ampere turns can be properly adjusted in the coil 36.

If now a current collector should engage the pan P with "power on", as already explained, a heavy current will flow through 15 the coil 9 which will pick the arm 13 up and into engagement with the contact 14. This prevents the flow of any current through the coil 5, but permits the flow of current through the coil 6 when the arm 19 20 has been picked up through the energizing of the coil 16 whereupon the plunger 8 will be moved outwardly and the switch tongue 4 moved to the "curve" position. The relation of the various parts immediately after 25 the collector has engaged the pan P with "power on" is shown diagrammatically in Fig. 5.

When the arm 13 is closed on the contact 14 and the arm 19 closed, as just described, 30 current will also flow through the coil 36, but in the opposite direction from that previously described and in the same direction as current through the coil 9 so that the two will work together and both act as holding 35 coils while the current collector is passing across the pan P with "power on", but as soon as the collector leaves the pan P then the coil 36 is the only holding coil to maintain the arm 13 in engagement with the contact 14. The ground for the coil 36 when 40 the arm 13 engages the contact 14 is by way of the switch arm 29. As soon as the arm 19 closes the switch C will start to function to drop the arm 29, but will do so through 45 differential action of the coils 27 and 28 due to the arm 13 being out of engagement with the conductor 35. As soon as the arm 29 opens it breaks the ground connection for the coil 36 and this coil then ceases to be a holding coil whereupon the arm 13 will 50 drop, but it cannot operate to energize the coil 5 for the reason that the arm 29 is open. As soon, however, as the arm 13 drops, the circuit through the coil 25 is opened and 55 this coil becomes deenergized and permits the arm 19 to drop. Immediately upon the dropping of the arm 19 the coil 27 is deenergized and the continued energization of the coil 28 will pick up the arm 29, returning the system to its normal condition as 60 shown in Fig. 2.

It has already been explained as to the flow of auxiliary car currents through the coil 9 which have a tendency, if sufficiently large, to pick up the arm 13 when the col-

lector engages the pan with "power off" unless the ampere turns of the coil 9 are so proportioned that this will not happen. It has also been explained in regard to the differential action of the coils 9 and 36 when 70 the collector engages the pan with "power off". It will be evident from this that the differential action of the coil 36 when the system operates with "power off" is beneficial as it tends to neutralize any picking up 75 effect of the coil 9.

If the collector should engage the pan P with "power off" and should come to rest with the collector engaging the pan, it will be necessary for the operator to throw his 80 controller to "power on" in order to proceed off the pan, and in this case the coil 9 might be sufficiently energized to pick up the arm 13 and current would then flow through the solenoid 6 thereby setting the switch in the 85 wrong direction as the arm 19 remains closed as long as the collector is on the pan. Therefore, I connect the contact 22 with the conductor 11 to coil 9 by the conductor 42, and it will be seen that when the arm 19 is closed 90 that there is a substantial shunt or short circuit placed about the coil 9 which will prevent a full flow of current through the coil 9 and prevent sufficient energization of the switch A to pick up the arm 13. In addition 95 to the shunt just described, the coil 36 which is energized until the arm 19 opens, acts as a differential to the coil 9 and, therefore, it will help to prevent a pick up of the arm 13 when the operator turns his controller to 100 "power on" under the conditions just described. The shunt or short circuit to the coil 9 will also prevent the operator from throwing the track switch in the wrong direction if he comes on the pan with "power off" and for some reason should inadvertently turn his controller to "power on" while 105 moving across the pan.

If, while moving across the pan with "power on" he should inadvertently move 110 his controller to "power off" while still on the pan the arm 13 cannot drop on account of the holding coil 36 until after the arm 29 has dropped, and then the current cannot flow to the solenoid 5.

There will be many changes and modifications in the system just described, such as possibly rearranging some of the connections and circuits, but which will still produce a system working within the scope of my invention.

I claim—

1. A switch operating system comprising in combination, a trolley conductor, a pan provided with two contact members to be 125 engaged by a current collector, an electrically operated track switch, a divided power circuit leading to said switch, an electrically operated selector switch connected to one of the contact members for controlling the said 130

power circuit to operate the track switch to a desired position, a normally open switch for opening and closing the power circuit, means connected to the other contact member 5 for closing the normally open switch and means to hold the switch closed while current is flowing therein to operate the track switch, normally closed opening means in one of the divided circuits for opening said 10 circuit after a predetermined time after the closing of the normally open switch and means controlling the selector switch and cooperating with the opening means to open the other divided circuit after the opening 15 means has opened.

2. A switch operating system comprising in combination, a trolley conductor, a pan provided with a pair of contact members to be engaged by a current collector, an electrically 20 operated track switch, a branched power circuit leading from the trolley conductor to the track switch, an electrically operated selector switch for controlling the power circuit to operate the track switch to 25 a desired position, a normally open switch to open and close the power circuit, means for closing the power circuit and means for holding the switch closed while current to operate the track switch is flowing in the 30 power circuit switch, normally closed means for opening one of the branch circuits after a predetermined time after the normally open switch has been closed, and means cooperating with the last said switch and with 35 the selector switch to open the other branch circuit after the normally closed switch has opened.

3. A switch operating system comprising in combination, a trolley conductor, a pan 40 to be engaged by a current collector, an electrically operated track switch, a normally open branched power circuit leading to the track switch, an electrically operated means normally closing one of the branch circuits 45 and opening the same after a predetermined time after the collector engages the pan, an electrically operated switch to close a second branch circuit when the collector engages the pan with "power on," and means interconnecting the switch and electrically operated 50 means to control their relative operation to open the second branch circuit after a predetermined time but after the first branch circuit has opened.

4. A switch operating system comprising in combination, a trolley conductor, a pan to be engaged by a current collector, an electrically operated track switch, a normally open branched operating circuit to conduct 55 an operating current to the track switch, a selector switch to control the said circuit so that the track switch will be operated in one direction or the other when the collector engages the pan with "power on" or "power off," electrically controlled means normally 60

closing one of the branch circuits and adapted to open after a predetermined time after current is supplied to the operating circuit, and means controlling the other branched circuit to open the same after the first 70 branch circuit has been opened by said electrically controlled means.

5. A switch operating system comprising in combination, a trolley conductor, a pan to be engaged by a current collector, an electrically 75 operated track switch, a normally open branched operating circuit to conduct an operating current to the track switch, a selector switch to control the said circuit to control the direction of operation of the track switch 80 when the collector engages the pan with "power on" or "power off," and electrically controlled means to open one branch circuit after the collector engages the pan with "power off" and to open said branch circuit 85 and control the opening of another branch circuit after the collector engages the pan with "power on."

6. A switch operating system comprising in combination, a trolley conductor, a 90 pan to be engaged by a current collector, an electrically operated track switch, a normally open branched operating circuit to conduct an operating current to the track switch, a selector switch to control the said 95 circuit to control the direction of operation of the track switch when the collector engages the pan with "power on" or "power off," electrically controlled means to open one branch circuit after the collector engages the pan with "power off" and to open 100 said branch circuit and control the opening of another branch circuit after the collector engages the pan with "power on" and means to normally hold that portion of the power 105 circuit leading to its branch circuits open and to close the same when the collector engages the pan.

7. A switch operating system comprising in combination, a trolley conductor, a pan, 110 to be engaged by a current collector, an electrically operated track switch, a normally open power circuit to conduct current to the track switch, a selector switch controlling said circuit to operate the track switch to 115 proper position when the collector engages the pan with "power on" or "power off," an electrically operated closing switch to close the power circuit when the collector engages the pan, a holding coil on said closing switch 120 and energized by the current in said power circuit to hold the closing switch closed after being initially closed and means for de-energizing the holding coil after a predetermined time after the closing switch is 125 closed.

8. A switch operating system comprising in combination, a trolley conductor, a pan to be engaged by a current collector, an electrically operated track switch, a power 130

- circuit, two branch circuits to conduct current to the track switch, a selector switch controlling the power circuit to operate the track switch to a predetermined position
- 5 when the collector engages the pan with "power off" or "power on" the car motors, means to close the selector switch to normally connect one branch circuit to the power circuit, means operating the selector
- 10 switch to connect the other branch circuit to the power circuit when the collector engages the pan with "power on", means controlling the selector switch tending to prevent the selector switch operating to close the second mentioned branch circuit when the power circuit and first branch circuit is closed and to hold the second branch circuit closed after being initially closed and means to control the opening and closing of the power circuit to the branch circuits.
- 15 9. In a switch operating system, the combination of a trolley conductor, a pan, an electrically operated track switch, a power circuit, branch circuits leading to the track
- 20 switch, a selector switch connecting the power circuit to the branch circuits to operate the track switch to different positions, electrically operated means controlling one branch circuit to open it after a predetermined time of flow of current therethrough and means controlling the other branch circuit to open the same after it has been closed by the selector switch, the last said means being controlled by the means controlling the first said branch circuit.
- 25 10. In a switch operating system, the combination of, a trolley conductor, a pan comprising two contact members to be engaged by a current collector, an electrically operated track switch S, a selector switch A for controlling the direction of operation of the track switch when the collector engages the pan with "power on" or "power off" by connecting to one or the other of two branch
- 30 circuits leading to the track switch, a normally open power circuit connecting the trolley conductor with the selector switch, an operating coil 9 for the switch A connected to the trolley conductor and to one contact member and energized sufficiently to operate the switch A with "power on" only; a switch B to close the power circuit when the collector engages the pan and having an operating coil connected to the other contact member and having a ground connection and operating to close the switch A and hold it closed while the collector engages the pan, the switch A also having a coil operating to hold the switch A closed while current is flowing in the power circuit and deriving its operating current from the power circuit;
- 35 a switch C normally closing one of the branch circuits leading to the switch S which operates the switch S with "power off", the switch C having two operating coils so connected that one holds the switch C normally closed and both hold the switch open while the switch B is closed and also operating to open the switch C after a predetermined time after the switch B is closed; an operating coil for the switch A so connected as to be energized whenever the system has been set in operation and in which the current flow tends to counteract the effect of current in the coil 9 when the system is working "power off" and tends to assist the current in the coil 9 when the system is working "power on", the said coil also operating to hold the switch A in the "power on" position when the switch A has been operated to the "power on" position and as long as the switch C is closed.

trolled by the switch B to prevent the switch A being moved to the "power on" position while the collector engages the pan if the switch A has been initially set for "power off" by the car operator.

12. In a switch operating system the combination of, a source of power, a contact device to be engaged by a current collector, an electrically operated track switch, a selector switch to control the operation of the track switch to a predetermined position when the collector engages the contact device with "power on" or "power off" and normally held in the "power off" position, and circuits connecting the parts for the above operation, the selector switch having a coil to operate it to the "power on" position and also having an operating coil in which the current flows in one direction when the system works "power on" and in the other direction when the system works "power off".

13. In a switch operating system the combination of, a source of power, a contact device to be engaged by a current collector, an electrically operated track switch, a selector switch to control the operation of the track switch to a predetermined position when the collector engages the contact device with "power on" or "power off" and normally held in the "power off" position, and circuits connecting the parts for the above operation, the selector switch having a coil to operate it to the "power on" position and also having an operating coil in which the current flows in one direction when the system works "power on" and in the other direction when the system works "power off", the direction of flow being determined by the selector switch being in the "power on" or "power off" position.

14. A switch operating system in combination, a trolley conductor, a pan to be engaged by a current collector, an electrically operated track switch, a normally open energizing circuit to conduct an operating current to the track switch, an electrically operated selector switch to control the direction of movement of the track switch, a switch B maintaining the energizing circuit normally open, means for closing the switch B when the collector engages the pan and to hold the switch B closed while the collector engages the pan and means dependent upon the current flowing through the track switch for holding the selector switch closed as long as an operating current flows in the energizing circuit.

15. A switch operating system comprising in combination, a trolley conductor, an electrically operated track switch, a normally open energizing circuit leading to the track switch, a circuit controlling means operated automatically when a car cooperates with the system to transmit current to the

track switch to operate the switch to the proper position and an electrically controlled switch operative when the car cooperates with the system to first close the circuit and maintain it closed while current is flowing therein to operate the track switch and thereafter so long as the car cooperates with the system.

16. A switch operating system comprising in combination, a trolley conductor, a pan to be engaged by a current collector, an electrically operated track switch, a normally dead energizing circuit connected to the track switch, a circuit controlling means for the energizing circuit operated automatically when the collector engages the pan to operate the switch in the proper direction, means other than the collector to energize the circuit when and while the collector engages the pan, and means to maintain the last said means operative and depending for its operation upon an operative current flowing through the track switch.

17. A switch operating system comprising in combination, a trolley conductor, a pan to be engaged by a current collector, an electrically operated track switch, a normally dead energizing circuit connected to the track switch, a circuit controlling means for the energizing circuit operated automatically when the collector engages the pan to operate the switch in the proper direction, means controlling the energizing of said circuit comprising means operated by the collector engaging the pan to supply current to the said circuit when and while the collector engages the pan and independent means operated by current derived from the said circuit while an operating current is flowing through the track switch.

18. In a mechanism of the class described, a normally open circuit, an electrically operated switch to close the circuit, a coil for operating the switch, means to be engaged and energized by the current collector on a car and connected to the coil, a coil for holding said switch closed and deriving its current from a trolley conductor and a normally closed switch to open the circuit at another point after a predetermined time after the circuit is closed.

19. A switch operating system comprising in combination, a trolley conductor, a pan, to be engaged by a current collector, an electrically operated track switch, a normally open power circuit to conduct current to the track switch, a selector switch controlling said circuit to operate the track switch to proper position when the collector engages the pan with "power on" or "power off", an electrically operated closing switch to close the power circuit when the collector engages the pan, a holding coil on said closing switch to hold the closing switch closed after being

initially closed and means for de-energizing the holding coil after a predetermined time after the switch is closed.

20. A switch operating system comprising an electrically operated track switch, a branched operating circuit therefor, a controlling switch for positioning said branched circuits and having an operating coil and connections to said coil, means to control the branches respectively of said branched circuit after a predetermined time.

21. A switch operating system comprising in combination, an electrically operated track switch, a branched operating circuit, a controlling switch therefor having an operating and a holding coil, means to de-energize the operating coil after it has functioned to operate the controlling switch and means to open the branches of the branched circuit after a predetermined time. 20

In testimony whereof I affix my signature.
GEORGE A. MEAD.
